RENÉ TOUCHELAY, OF LA CALLE, ALGERIA

AUTOMATIC THERMIC IGNITION DEVICE FOR INTERNAL-COMBUSTION ENGINES

Application filed August 13, 1928, Serial No. 299,312, and in France March 14, 1928.

The present invention relates to a thermic ignition device of the automatic type which is adapted for the ignition of the explosive mixture in internal combustion engines. 5 The said ignition device forms an extension of the operating chamber of the engine cylinder upon which it is disposed, and said device may be heated by an external source of heat. The device is terminated at the 10 top by a tightly closed chamber. The said chamber contains two nickel blocks which are provided with cooling flanges whereby their surface of contact with the explosive mixture will be increased. They are provided with orifices affording access to the 15 interior of said chamber.

The appended drawings show by way of example an embodiment of the invention.

Fig. 1 is an elevational view of a constructional form of the said apparatus, and Fig. 2 is the corresponding vertical section.

Fig. 3 is a detail plan view of the construction.

The apparatus comprises a socket or base 25 1 by which it is mounted on the wall of the engine cylinder. The said base is provided with cooling flanges, the upper flanges being polygonal so that the device may be screwed, with the interposition of a plastic 30 metal packing member 2, a coupling piece 3 provided with large flanges, and supporting at the top and through the medium of a screw thread and a second plastic metal packing member 4, the explosion chamber 35 5 which contains two blocks 6 of pure nickel 6 separated by a nickel diaphragm 7 and held together by a nickel tube 8 placed at the center and crimped or upset at each end. The said blocks are pierced with the 40 orifices 9 by which their internal recess is connected with the remainder of the explosion chamber. This latter is provided at the exterior with the asbestos element 10 which is held in place by the pressed metal 45 cap 11. It is hermetically closed at the up-

per part by the hemispherical cap 12 which is held in place by the flanged nut 13, with the interposition of plastic metal packing above and below, as shown at 14 and 15. Apertures 16 are formed in the said cap for 50 the exit of the heat produced by the starting apparatus, and an aperture 17 corresponding to a bayonet joint enables the latter to be secured.

The operation is as follows. 55

For starting purposes, the cap 12 is heated by suitable means such as an air-acetylene burner, secured to the said cap by the bayonet joint 17, and the engine crankshaft is driven in such manner as to proceed upon 60 the compression stroke, as for the usual starting. The fresh gas delivered into the apparatus, and thence into the central tube 8 will be ignited when in contact with the hemispherical cap 12 which is heated to 65 redness, but it is maintained at the end of the explosion chamber 5 and the collecting members 6 by the constantly increasing pressure due to the upward stroke of the piston. When the said piston attains the upper dead 70 center, a slight vacuum will be formed which allows the explosion to be propagated through the body of the gas. In this manner the combustion is complete, and this represents the power stroke. I thus obviate 75 all pounding due to a premature complete ignition, and the point of ignition is automatically determined according to the upper dead center, that is, after the rate of maximum compression commences to decrease. 80

It is obvious that after a certain number of explosions the collecting members 6 will be heated to such a degree as to dispense with all external heating since the heat accumulated during each explosion will be, 85 even at slow speed, much greater than what is required for each ignition. The asbestos packing 10 serves to protect the explosion chamber 5 against the variations of external temperature. 90

As concerns the bases or sockets 1 and 3, these serve exclusively to assure the maximum break in the heating and to separate the heated explosion chamber from the relatively cold cylinder head of the engine, while sufficiently cooling the gas stream traversing the same, for an excessive heating at this point would no doubt cause an improper ignition, and hence the pounding of the engine.

10 Since the said ignition device is screwed to the cylinder of an engine already provided with its usual ignition means, it will rapidly heat up when the engine is started, and will thus act alone to assure the ignition should the normal ignition means fail. This effect takes place automatically without any external heating, and even without the driver's knowledge. For this reason, the said device will thus provide for the practical elimination of all ignition failures.

15 The said invention has further for its object to cover not only the aforesaid apparatus but all other apparatus of like nature, differing in the arrangements or details of construction, whether fixed or movable, or made in one or several pieces; or provided with water or air cooling, and in short, for all purposes adapted for ignition 20 in an internal combustion engine, by analogous means, utilizing the ignition upon an external heated surface which is independent of the engine cylinder itself.

25 I claim:

30 The automatic thermic ignition device for internal combustion engines is characterized in that:

35 1. An igniter of the class described comprising a casing formed with a chamber 40 open at the bottom, hollow heating elements mounted in the chamber and spaced from the walls of the latter and formed with openings, means for separating the hollow heating elements, a tubular element 45 open at both ends and extending through the heating elements and secured to the ends thereof, and a heater cap secured to the upper end of the casing and engaging the upper heating element.

40 50 2. An igniter of the class described comprising a casing formed with a chamber open at the bottom, hollow heating elements mounted in the chamber and spaced from the walls of the latter and formed with 55 openings, said heating elements having ribs on their outer surfaces, means for separating the hollow heating elements, a tubular element open at both ends and extending through the heating elements and secured 60 to the ends thereof, a heater cap secured to the upper end of the casing and engaging the upper heating element, and insulation surrounding the chamber walls.

65 3. An igniter comprising a casing formed with a chamber, a heating unit mounted in

the chamber and spaced from the side walls thereof, said heating unit comprising a pair of hollow elements, each formed with an opening, a plate separating the hollow elements, a tube open at both ends and communicating with the chamber and secured to the outer ends of the hollow elements, and a heater cap secured to the casing and engaging the heating unit.

70 75 In testimony whereof I affix my signature.

RENÉ TOUCHELAY.
